ELECTRIC CANDLE LAMP

Original Filed Dec. 29, 1920 2 Sheets-Sheet 2

Fig. 9.

UNITED STATES PATENT OFFICE.

MORDUCH L. KAPLAN, OF BROOKLYN, NEW YORK.

ELECTRIC CANDLE LAMP.

Application filed December 29, 1920, Serial No. 433,784. Renewed June 6, 1928.

To all whom it may concern:

Be it known that I, MORDUCH L. KAPLAN, a citizen of the United States, and a resident of Brooklyn, in the county of Kings and State of New York, have invented certain new and useful Improvements in Electric Candle Lamps, of which the following is a specification.

The invention pertains to the class candle lamps possessing a battery and an electric light bulb and adapted to stand on a table or the like, said lamps being provided with a switch for making and breaking the circuit through the battery and lamp, and the invention has for its purpose to simplify and cheapen the cost of electric candle lamps and to provide an electric candle lamp comprising only two units, to-wit: a battery and a detachable cap or top member to be applied thereto and carrying the lamp bulb and switch. When the battery has become exhausted, the cap is removed therefrom and placed upon a new battery, thus restoring the candle lamp for further use. In accordance with my invention I dispense with the expensive metallic casings which usually receive the battery of electric candle lamps and provide a candle lamp consisting essentially and only of the battery and the detachable cap or dome-like top member, the cap being equipped with a socket to receive the lamp-bulb and with a switch for making and breaking the circuit.

My invention may be carried into effect in several modified forms, and said invention and preferred means embodying the same will be fully understood from the detailed description hereinafter presented, reference being had to the accompanying drawings, in which:

Fig. 1 is a vertical section through a candle lamp constructed in accordance with my invention;

Fig. 2 is a side elevation of the same, on a smaller scale, taken from the left hand side of Fig. 1, the paper or like covering on the battery being partly broken away for the purpose of disclosing one of the conductors;

Fig. 3 is a detached perspective view of a sleeve of fibre or other insulating material which I apply within the upper end of the top cap and which receives the metallic parts engaging the lamp bulb and carbon pole of the battery;

Fig. 4 is a detached side elevation of the means held within the sleeve shown in Fig. 3, for engaging the lamp bulb and carbon pole of the battery.

Fig. 5 is a sectional view through the same and said sleeve showing these parts in the relation they occupy before being applied upon the carbon pole of the battery;

Fig. 6 is a bottom end view of the same;

Fig. 7 is a sectional view through the upper portion of an electric candle lamp embodying my invention and employing a modified construction of switch for making and breaking the circuit;

Fig. 8 is a horizontal section through the same, taken on the dotted line 8—8 of Fig. 7;

Fig. 9 is a side elevation, partly broken away and partly in section, of the construction shown in Figs. 7 and 8;

Fig. 10 is a side elevation, partly broken away and partly in section, of the upper portion of a candle lamp embodying my invention and illustrating a further modification thereof;

Fig. 11 is a bottom view of the upper portion of the same detached from the battery;

Fig. 12 is a detached face view of the slotted ring conducting member shown in Figs. 10 and 11;

Fig. 13 is a side elevation, partly in section and partly broken away, of the upper portion of a candle lamp constructed in accordance with my invention and illustrating a modification thereof; and

Fig. 14 is a corresponding view of a further modified embodiment of my invention.

In the drawings, referring to Figs. 1 to 6 inclusive, illustrating one embodiment of my invention, 20, 21 designate the cells of the battery, which for convenience, I will indicate as a whole by the numeral 22. The cells 20, 21 are arranged as usual, with the negative or zinc pole 23 of the upper battery cell engaged with the carbon pole 24 of the battery cell below it, and said cells 20, 21 in the completion of the battery are enclosed in a paste-board cylinder or the like 25 which insulates and keeps the cells together and permits them to be handled as a single battery. 26 denotes the carbon pole of the upper battery cell 21, and it will preferably be of the shape shown, to-wit, having a lower neck portion and an upper head portion. The carton 25 enclosing the battery cells 20, 21 and creating a plural cell battery

22 may be wrapped with an ornamental character of paper or the like 27 as a finish for the candle lamp, which is broad enough at its lower end to stand securely upon a 5 table and does not require the presence of the usual expensive metallic holders with which electric table lamps are customarily provided. I secure to the zinc of the lower battery cell 20 a conducting strip 28 which 10 extends upwardly between the carton 25 and wrapping 27 and is bent over the upper end of the battery cell 21 to form a convenient terminal 29, the carton 25 at the lower end of the strip 28 being cut away, as shown in 15 Figs. 1 and 2, to admit of the lower end of said strip being soldered to the zinc of the cell 20.

Upon the upper end of the battery 22 is 20 attached a cap or dome 30 which supports the features of my invention and which may be removed from one battery and placed upon another battery whenever occasion may so require.

The cap or dome 30 may be of cast or sheet 25 metal or of other suitable material, and at its lower edge is preferably flanged, as shown in Fig. 1, to rest upon the upper edges of the carton 25 and covering material 27. In the present instance the dome or cap 30 is shown 30 as formed of cast metal and resting upon the terminal 29 of the conducting strip 28, said cap or dome being thus in electrical connection with the zinc of the battery cell 20. The cap or dome 30 is preferably of 35 truncated cone-shape so as to resemble approximately the upper end of the conventional form of a candle, the sides of the cap or dome converging on graceful lines upwardly and terminating in a sleeve portion 40 31. Within the cap or dome 30 I provide a vertical sleeve or cylinder 32 of insulating material, said sleeve being firmly gripped at its upper end within the contracted sleeve portion 31 of the cap or dome 30, while at its 45 lower portion said sleeve 32 extends downwardly into approximately near relation to the upper end of the battery cell 21. Within the upper end of the sleeve 32 I provide a metal lamp socket 33, said socket being of 50 cylindrical outline and threaded and tightly held within the upper end of the sleeve 32 in position to receive the terminal 34 of the lamp bulb 35. Within the lower portion of the sleeve 32 is provided an inverted sheet 55 metal cap-like clutch 36 whose sides are slit to form spring members 37 which normally converge inwardly and have outwardly flaring lower edges, as shown in Figs. 4 and 5. The clutch member 36 is connected with the socket 33 by means of a vertical screw 38 whose head bears upon a fiber washer 39 within the lower end of the socket 33 and whose lower end is arranged 60 to engage the upper end of the positive pole 26 of the battery cell 21. A washer of in-

sulating material 40 is interposed between the bottom of the socket 33 and top of the clutch member 36, and upon the lower end of the screw 38 is provided a nut 41 for securing the parts together. The screw 38 70 passes through a large opening in the bottom of the socket 33, and by not engaging said socket but engaging the fiber washer 39, becomes insulated from said socket. The fiber washer 40 insulates the socket 33 from the 75 metal clutch member 36. The head of the screw 38 forms an electric contact point for the lower terminal 42 of the lamp 35, while the other terminal of said lamp is in electrical engagement with the socket 33. The 80 cap or dome 30 carries the fiber sleeve 32 and all of the parts connected therewith and, with said sleeve and its connections, may be handled as a unit and applied to and removed from the battery 22 at will. 85

In applying the cap or dome 30 and its parts to the battery 22 it is only necessary to shove the socket member 36 downwardly upon the head of the carbon pole 26 of the battery, this action serving to properly 90 locate the lower edge of the cap or dome around the upper edge of the battery and effect the electrical connection of the cap or dome with the terminal 29 of the conducting strip 28. When the clutch member 36 95 is forced downwardly on the carbon pole 26 the head 43 on said pole 26 becomes wedged within the clutch member 36 and forces the spring members 37 outwardly against the inner walls of the tube or cylinder 32, or to the position in which said spring members 10 37 are shown in Fig. 1. The action of the spring members 37 against the head 43 serves to detachably lock the cap or dome 30 and its parts upon the battery. The lamp 10 bulb 35 will be screwed into the socket 33, as usual, and said lamp bulb may be replaced as often as may be required without removing the cap or dome 30 from the battery.

Upon the side of the cap or dome 30 I 11 provide a slidable thumb-piece 44 connected with a sliding switch 45, whose upper end is disposed within the slot 46 cut in the side of the fiber sleeve 32. When the thumb-piece 44 is pushed upwardly, the upper end of the switch 45 will engage the side of the lamp socket 33 and afford an electrical connection from the zinc of the battery cell 20 through the conducting strip 28, cap or dome 30, switch 45 and socket 33 to the terminal 34 of the lamp bulb, whence the circuit will be from the terminal 42 of the lamp through the screw 38 to the carbon pole 26 of the battery, this completing the circuit 11 12 through the lamp and causing the latter to light. The circuit may be broken and the light extinguished by sliding the thumb-piece 44 downwardly to remove the switch 45 from electrical contact with the lamp 12 13 socket 33. 130

The candle lamp shown in Figs. 1 to 6 inclusive comprises two unitary parts, one being the battery 22 and the other the cap or dome 30 and features carried by it. 5 When the battery becomes exhausted the cap or dome 30 may be removed from it and placed upon a fresh battery. The candle lamp is inexpensive of manufacture and easily cared for and manipulated, and said 10 candle lamp may be set upon a table or carried about with the hand grasped upon the battery 22. I have also found that the cap or dome 30 so tightly clings to the battery that the entire article may be lifted by taking hold of the cap or dome 30. The head 15 43 on the positive pole 26 of the battery should be of such size so as to be firmly engaged by the clutch member 36, and said head 43 may consist simply of a metal cap 20 driven upon the upper end of the pole member 26, sufficiently indicated in Fig. 13.

In my construction of candle lamp I employ as aforesaid two essential features, to-wit, the battery and the dome or cap 30, 25 with its parts, and it is to be observed that the cap or dome 30 is detachably connected with the battery, and that in accordance with my invention I do not employ the expensive metal parts at present required in 30 electric candle lamps. The covering material 27 on the battery will be made sufficiently attractive to cause the candle lamp to have an ornamental appearance, and said covering material may be of paper, linen 35 or other convenient material.

In Figs. 7, 8 and 9 I illustrate a modified construction of my invention, and in these figures 46 denotes the battery, 47 the dome or cap therefor and 48 the lamp bulb, which is held in a metallic threaded lamp socket 49 soldered within the upper contracted end portion 50 of the cap or dome 47. The cap or dome 47 has secured to its lower flanged edge, where it rests on the battery 46, a fibre ring 51 and a fibre disk 52 which has an open center, as at 53, and is cut out at one side, as at 54, to expose the free end of a switch spring 55 secured by rivets to the upper face of the fibre washer 52, said free end of the switch spring 55 being directly over and flanged downwardly to permanently engage a terminal 56 formed by bending inwardly over the battery the upper end of a conducting strip 57, which corresponds with the conducting strip 28 of Fig. 1 and at its lower end will be connected with the zinc or negative pole of the battery correspondingly with the construction shown in Fig. 1. The lamp socket 49 has secured to its lower portion a fibre or other insulating tube 58 and within the lower end of this tube 58 is secured the invert-clutch member 59 which corresponds with the clutch-member 36 of Figs. 1 to 6 inclusive, being of sheet metal and having spring members 60 to be forced upon the

head 43 of the positive pole element 26 of the battery. The clutch-member 59 is connected with the lamp-socket 49 by means of a screw 61 whose head is engaged by the lower terminal of the lamp-bulb and whose lower end engages the head 43 of the positive pole element 26 of the battery, an insulating washer 62 being provided below the head of the screw and an insulating washer 63 being provided between the lamp socket 49 and clutch-member 59, said screw and insulating washers corresponding with the construction shown in Figs. 1 and 5. Upon the side of the cap or dome 47 is provided a turn-button or head 64 mounted on a pin 65 which has a bearing in the side of the cap or dome 47 and at its inner end carries an arm 66 which, when turned downwardly will engage the switch-spring 55 which is against the terminal 56 to complete the circuit through the battery and lamp and which, when turned from said spring 55, will break the circuit. The circuit is from the negative pole of the battery through the conductor 57, switch-spring 55, arm 66, cap or dome 47 and lamp-socket 49 to one terminal of the lamp and from the other terminal of the lamp through the screw 61 to the positive pole of the battery.

The cap or dome 47 with all of its own features may be detached from and applied to the battery in the same manner that the cap or dome shown in Fig. 1 may be attached to and removed from the battery. Figs. 7, 8 and 9 illustrate a modified construction of means for carrying out my invention, and in view of the detailed description of the construction shown in Fig. 1, that illustrated in Figs. 7, 8 and 9 will be understood without further explanation.

Figs. 10, 11 and 12 present a further modified construction embodying my invention, and therein 67 denotes the battery, 68 the cap or dome carrying the features to be applied to the battery for producing a candle lamp, 69 the lamp bulb and 70 a fibre or other insulating tube held at its upper end by the lamp socket set within the contracted neck portion 71 of the cap or dome 68, said tube 70 corresponding exactly with the tube 58 shown in Fig. 7. The fibre tube 70 contains the lamp socket 49, clutch-member 59, screw 61 and fibre washers 62, 63 exactly as shown in Fig. 7 and therefore not fully illustrated in Figs. 10 and 11. The clutch-member in Figs. 10 and 11 is shown at 72 and engages the positive pole element 73 of the battery 67. The screw of Fig. 11 corresponding with the screw 61 of Fig. 7, I number 74.

Upon the lower flanged edge of the cap or dome 68 is secured a fibre ring or washer 75, and to this ring or washer is secured a slotted conducting disk-like plate 76 having a series of inwardly and downwardly extend-

ing radial spring-sections 77 some one of which will, when the cap or dome 68 is applied upon the battery, engage the upper terminal 78 of the battery conducting strip 79, as shown in Fig. 10, the upper end of said strip 79 being folded over upon the upper end of the battery so that no matter in what relation the cap or dome 68 may be applied upon the battery, one or more of the 10 spring contact sections 77 will engage the terminal 78. The purpose of having the ring of contact sections 77 is to make it unnecessary to use any special care in applying the cap or dome 68 upon the battery. The 15 circuit is made from the slotted ring or plate 76 up through the cap or dome 68 to the lamp socket by means of a push-button or slide 80 whose stem passes through a slot 81 in the cap or dome 68 and carries on its 20 inner end a conducting arm 82 adapted, when the slide 80 is moved downwardly to the position shown in Fig. 10, to enter into electrical engagement with the ring or plate 76, thereby to make the circuit from the conducting strip 79 to the lamp socket. When 25 the slide 80 is pushed upwardly on the side of the dome or cap 68, the arm 82 will be carried from the plate or ring 76 and the circuit will be thereby broken.

30 Fig. 13 presents an embodiment of my invention in which the circuit is made and broken by a rotary movement of the cap or dome, no other switch mechanism being present, and therein 83 denotes the battery, 35 84 the conducting strip at the side thereof, 85 the upper terminal of said strip formed by bending the end of the strip over upon the top of the battery, 86 the cap or dome, 87 the lamp, 88 the lamp-socket secured 40 within the upper contracted end of said dome, 89 the positive pole element of the battery, 90 a cap tightly fitting upon and preferably not detachable from said positive pole element, and 91 a screw connecting the lamp-socket 88 with the cap 90 and which is in circuit with the lower terminal of the lamp and said cap, a fibre washer 92 being provided within the socket 88 below the head of the screw 91 and a fibre washer 45 93 being interposed between the lower end of said socket 88 and a nut 94 provided on the screw 91 and firmly engaging said washer 93. The lower threaded end of the screw 91 enters a threaded hole in the cap 90. When the cap or dome 86 is rotated 50 to work the screw 91 downwardly through the cap 90, the lower flanged edge of the dome will be pressed against the upper bent end of the conducting strip 84 and at that 55 time the circuit will be from the strip 84 through the dome 86 and lamp socket 88 to one terminal of the lamp 87 and thence through the lower terminal of said lamp, screw 91 and cap 90 to the positive pole or element 89 of the battery. When the dome 60

86 is reversely rotated, the cap or dome will be elevated by reason of the engagement of the screw 91 with the cap 90, and this will result in the lower flanged edge of the cap or dome leaving the conducting strip 84 70 and in the breaking of the circuit.

In Fig. 14 I illustrate a further embodiment of my invention in which the circuit is made and broken by a rotary movement of the cap or dome, and therein 95 designates 75 the battery, 96 the usual conducting strip thereof, 97 the upper terminal of said strip extending inwardly over the battery, 98 the metallic cap or dome, 99 the lamp, 100 the threaded lamp socket secured within the 80 upper contracted end of said dome, 101 a threaded positive pole element or screw at the upper end of the battery, 102 a cap or the like mounted upon and engaging the thread of said screw, and 103 the screw connecting the lamp socket 100 with the cap 102, a fiber washer 104 being interposed below the head of said screw and a fiber washer 105 being interposed between the lower end of the lamp socket 100 and the upper end 90 of the cap 102. In the construction shown in Fig. 14, when the cap or dome 98 is rotated to work the cap 102 downwardly on the positive pole element or screw 101, the lower flanged edge of the cap or dome 98 95 is moved against the upper end portion of the strip 96 and the circuit will then be completed through the battery and lamp. When the cap or dome 98 is reversely rotated it will, by reason of the engagement of the cap 100 102 with the screw 101, become elevated from the conducting strip 96, and thereby the circuit through the lamp will be broken.

In Fig. 13 the screw 91, on the rotation of the cap or dome 86, effects the movement of 105 said cap or dome 86 to make or break the circuit, and in Fig. 14 the rotation of the cap or dome 98 effects the making or breaking of the circuit due to its depression or elevation by the action of the screw 101. 110

It will be understood from the foregoing description that several forms of make-and-break switches may be made use of in connection with the features constituting my invention. I desire it understood also that 115 in some desirable embodiments of my invention, the circuit may be made and broken by manually turning the lamp bulb to effect that result. If, for illustration, the cap 86 of Fig. 13 is allowed to remain in its lower 120 position against the terminal 85, the circuit may be broken by turning the lamp 87 to move upwardly and carry its lower terminal from the screw 91, thus extinguishing the light, and said circuit may be again established whenever desired by screwing the lamp 87 downwardly until its lower terminal again engages the screw 91. I may therefore use the lamp-bulb as a make-and-break switch. In the construction shown in Fig. 125 130

14, the lamp-bulb may, also, be employed for making and breaking the circuit.

In all of the forms of my invention hereinbefore described I employ batteries capable of standing on end, and a removable cap or dome carrying the lamp and other features adapting it, in connection with the battery, to create a suitable candle lamp. I have presented several embodiments of my invention as illustrative of the preferred ways of carrying the same into effect. I am aware of other modifications of my invention, and hence I do not desire to be limited to the details of construction presented, but wish to secure adequate protection for the invention regardless of such modifications as may suggest themselves in carrying out the objects and purposes of the invention, except as limited by the claims.

20 What I claim as my invention and desire to secure by Letters-Patent, is—

1. An electric candle-lamp of the character described, comprising a battery adapted to stand on end and having an upwardly projecting positive element and a conducting strip extending from its negative element to the upper end of the battery and bent over upon the same, a dome of conducting material detachably mounted on the upper end of the battery and adapted to engage said strip and having means for firmly securing it to the upwardly projecting positive element of the battery, and an electric lamp bulb detachably socketed in the apex of the dome with one terminal in electrical connection with the positive element of the battery.

2. An electric-battery-lamp comprising a battery of the character described having an upwardly projecting positive element, a hollow cap detachably mounted over and covering the upper end of said battery and carrying an electric lamp bulb, means carried by and within said cap for firmly securing it to the said positive element of the battery, said lamp on the application of said cap to position being adapted to become electrically connected at one terminal with said positive element, and means for effecting the connection of the negative element of the battery with the other terminal of the lamp bulb, for completing the circuit.

3. An electric-battery-lamp comprising a battery of the character described having an upwardly projecting positive element and a conducting strip extending from the negative pole of the lower element of the battery to the upper end of the battery, a hollow cap detachably mounted over the upper end of said battery and adapted at its outer edge to be brought into electrical engagement with said strip, an electric lamp bulb carried by said cap, and means carried by and within said cap for firmly securing it to the said positive element of the battery, said lamp on the application of said cap to

position being adapted to become electrically connected at one terminal with said positive element of the battery.

4. An electric-battery-lamp comprising a battery of the character described having an upwardly projecting positive element and means bringing the negative pole of its lower cell to the upper end of the battery, a hollow cap having a lower diameter about equal to the diameter of and detachably mounted over the upper end of the battery and being adapted to be brought into electrical connection with said negative pole, a threaded socket within said cap having and carrying at its lower end a conductor insulated from said socket and adapted to be placed in electrical connection with said positive element when the cap is positioned, means associated with said socket for firmly securing said cap to said positive element, and a lamp-bulb threaded in said socket and adapted at one terminal to engage said conductor.

5. An electric-battery-lamp comprising a battery of the character described having an upwardly projecting positive element and means bringing the negative pole of its lower cell to the upper end of the battery, a hollow cap having a lower diameter about equal to the diameter of and detachably mounted over the upper end of the battery and being adapted to be brought into electrical connection with said negative pole, a threaded socket within said cap having and carrying at its lower end a conductor insulated from said socket and adapted to be placed in electrical connection with said positive element when the cap is positioned, means for firmly, though detachably, binding said conductor to said positive element and thereby securing said cap in position, and a lamp-bulb threaded in said socket and adapted at one terminal to engage said conductor.

6. An electric candle-lamp of the character described, comprising a battery adapted to stand on end and having an upwardly projecting positive element and a conducting strip extending from its negative element to the upper end of the battery and bent over upon the same, a dome of conducting material detachably mounted on the upper end of the battery and adapted to engage said strip and having means for firmly securing it to the upwardly projecting positive element of the battery, an electric lamp bulb detachably socketed in the apex of the dome with one terminal in electrical connection with the positive element of the battery, and means for making and breaking the circuit from said strip through said dome to the other terminal of the lamp bulb.

7. An electric candle-lamp of the character described, comprising a battery adapted to stand on end and having an upwardly projecting positive element and a conduct-

- ing strip extending from its negative element to the upper end of the battery and bent over upon the same, a dome of conducting material detachably mounted on the 5 upper end of the battery and adapted to engage said strip and having means for firmly securing it to the upwardly projecting positive element of the battery, an electric lamp bulb detachably socketed in the 10 apex of the dome with one terminal in electrical connection with the positive element of the battery, and a manually operative switch mounted on the side of said dome for completing the circuit from said dome 15 to the other terminal of the lamp, said dome being normally insulated from said other lamp terminal.
8. An electric candle-lamp of the character described, comprising a battery adapted to stand on end, a dome of conducting material superimposed on said battery and having a spring clutch of conducting material gripping the upwardly projecting positive element of the battery, a lamp socket in 20 the apex portion of said dome and insulated from said clutch, a central conductor connecting said socket and clutch and insulated from said socket and in electrical connection with said clutch, an electric lamp 25 bulb held in said socket with its lower terminal in electrical engagement with said central conductor, and manually operative means for effecting the electrical connection through said dome of the negative element 30 of the battery with said lamp socket, for completing the circuit.
9. An electric candle-lamp of the character described, comprising a battery adapted to stand on end, a dome of conducting material superimposed on said battery and having a spring clutch of conducting material gripping the upwardly projecting positive element of the battery, a lamp socket in the apex portion of said dome and insulated from said clutch, a central conductor 40 connecting said socket and clutch and insulated from said socket and in electrical connection with said clutch, an electric lamp bulb held in said socket with its lower terminal in electrical engagement with said central conductor.

tral conductor, an insulating sleeve connecting and closely binding around said lamp socket and said clutch and restraining the members of said clutch against undue outward movement, and manually operative means for effecting the electrical connection through said dome of the negative element of the battery with said lamp socket, for completing the circuit.

10. An electric candle-lamp of the character described, comprising a battery adapted to stand on end, a dome of conducting material superimposed on said battery and having fastened therein a sleeve of insulating material, a lamp socket in the upper portion of said sleeve, a spring clutch in the lower portion of said sleeve adapted to grip the upwardly projecting positive element of the battery and insulated from said socket, a central conductor connecting said socket and clutch and insulated from said socket and in electrical connection with said clutch, an electric lamp bulb held in said socket with its lower terminal in electrical engagement with said central conductor, and a manually operative switch on said dome for completing the circuit from the negative element of the battery through said dome to said lamp socket.

11. An electric-battery lamp of the character described, comprising two main parts, one being a plural cell battery having the negative element of its lower cell carried to the upper end of the battery, and the other being a conductive cap or dome carrying an electric lamp bulb detachably applied thereto and also conductive means depending from within and insulated from and concealed by said cap or dome for detachably securing said cap or dome over the battery and to the positive element thereof and also against said negative element at the upper end of the battery, said conductive securing means being positioned for electrical connection with one terminal of said lamp bulb.

Signed at New York city, in the county of New York and State of New York, this 28th day of December, A. D. 1920.

MORDUCH L. KAPLAN.
